MAGNETRON TUBE MAGNET STRUCTURE

Theodore A. Haddad, Swarthmore, Pa., assignor to Burroughs Corporation, Detroit, Mich., a corporation of Michigan

Application March 15, 1956, Serial No. 571,649

7 Claims. (Cl. 315—8)

This invention relates to a plurality of magnetron tubes operating in close proximity and more particularly concerns a plurality of magnetron beam switching tubes in a structure enabling their stable operation in a close-proximity cluster.

Magnetron beam switching tubes are most conveniently and economically provided with the necessary axial magnetic field by enclosing the tube elements and their envelope in a cylindrical permanent magnet which maintains flux through the tube along lines parallel to the tube's axis. With such a uniform distribution of magnet structure around the tube, this magnetic field is substantially uniform in the area occupied by tube electrodes. Further, any slight variation in field strength is symmetrical about the axis of the tube so that the behavior of all beam-holding positions around the tube are the same with respect to static beam holding and dynamic beam switching or forming. Tube operation is affected by disturbance of this magnetic field's axial alignment and symmetry.

When it is attempted to operate such magnet-encased tubes in close proximity to each other, they cease to operate reliably at separations less than about four inches between centers. The respective magnetic fields interact upon each other, disturbing their axial alignment and upsetting their axial symmetry to a serious degree. This has imposed a serious handicap upon use of magnetron beam tubes in compact clusters of a plurality of such tubes.

An important object of this invention is to provide a magnetic structure associated with a plurality of magnetrons and enabling their stable operation in a compact cluster.

Another important object of this invention is to provide a low reluctance magnetic structure between pairs of a plurality of magnetrons to control magnetic field patterns and enable each tube to function reliably while in close proximity to other tubes of the plurality.

In accordance with this invention there are provided bars of low reluctance, high permeability material having low residual magnetism, interposed between adjacent cylindrical magnets of magnetron beam switching tubes at their points of nearest proximity, conducting the external magnetic fields of these magnets so as to prevent interaction between the respective magnetic fields.

For a more detailed understanding of this invention reference is made to the drawings in which:

Fig. 1 is a perspective view of a pair of magnetron beam switching tubes with a low reluctance metallic bar between them;

Fig. 2 is a schematic representation of the magnetic flux lines of a cylindrical magnet such as used on a magnetron beam switching tube;

Fig. 3 is a schematic representation of the magnetic flux lines of two cylindrical magnets in close proximity;

Fig. 4 is a schematic representation of the magnetic flux lines of two cylindrical magnets in close proximity, with a low reluctance member interposed; and

2

Fig. 5 is a plan view of a cluster of magnetron tubes with interposed low-reluctance members to permit close proximity within the cluster.

The magnetron beam switching tubes as shown in Fig. 1 are as described and claimed in United States Patent No. 2,721,955, issued to Sin-pih Fan and Saul Kuchinsky entitled "Multi-Position Beam Tube." By use of the crossed electric and magnetic fields of a magnetron type structure and of a number of electrodes in successive arrays around a cathode, this tube can provide a high-current electron beam to a plurality of output electrodes in rapid succession and with great reliability.

As shown in Fig. 1, a cylindrical magnet 21 encloses tube 20 and provides an axial magnetic field therethrough. Tube 20 contains a central axial cathode 22 surrounded by several concentric arrays of electrodes. On a circular locus nearest to the cathode are the beam forming and holding electrodes 23, called spade electrodes. Beyond the spade electrodes on another circular locus are the target electrodes 24, positioned peripheral to this circle so as to cover the inter-spade spaces and to collect beam current flowing into such spaces between spades. Intermediate between one edge of each spade and the near edge of each target proximate to that spade are the switching grid electrodes 25. These grids also are on a circular locus centered on the cathode 22.

With the cathode heated to electron emission temperature and a positive potential on the spade electrodes and target electrodes, the magnetic field from magnet 21 is above that value required for magnetron type cut-off of current in the tube and no current will flow. However, if one of the spade electrodes is reduced in potential to about half its previous potential, the voltage gradients within the tube are distorted and a beam will form. This electron beam grazes the low potential spade and strikes the adjacent target electrode. A small portion of the electron beam does flow to this spade. With a suitable series resistor interposed in the connection of each spade to its positive voltage supply, this small portion of the beam current produces an IR drop which enables the spade to hold the beam stably in place once it grazes that spade.

Switching grid electrodes 25 upset this stable beam holding condition when a suitable negative potential is applied to the grid which is in the same inter-spade space as is the beam. As this grid goes negative, the beam fans out across the target electrode and some of it strikes the next spade electrode. This fraction of beam current produces another IR voltage drop which lowers the potential of this next spade. With a lowered potential on the next spade, the beam switches over to the next target. This switching action occurs at a very rapid rate, the time required to switch from one target to the next being in the order of one-tenth of a microsecond.

When two tubes 20 and 20', positioned on a common surface such as a chassis, are brought any closer than a few inches between centers, about three or four inches, without the precautions prescribed by the present invention, they cease to be capable of reliable operation. However, interposition of low reluctance bar 30 permits reliable operation even with magnets 21 and 21' so close as to contact bar 30. Bar 30 controls the external fields of magnets 21 and 21' to prevent interaction, as will be described.

In Figs. 2, 3 and 4, the details of envelope 26 and tube electrodes 22 to 25 are not shown, inasmuch as they do not materially affect the magnetic field of magnet 21 which surrounds them.

To achieve the needed inner magnetic field for operation of tube 20, magnet 21 has an overall magnetic

field as shown in Fig. 2 with lines of force centered about the tube electrode axis. With the electrodes of tube 20 assembled for clockwise beam advancement, and correspondingly for counter clockwise motion of electrons within the beam and in the cathode-to-anode space, when seen in top plan view, it is imperative that each tube's cylindrical magnet 21 be positioned to present its south pole at the top and its north pole at the bottom of the cylinder.

When two tubes and their magnets 21 and 21' are brought into close proximity as shown in Fig. 3, their magnetic fields interact. Similar magnetic poles are being brought close together, so the flux lines from adjacent magnets repel each other. The two south poles at the top of adjacent magnets are receiving flux lines which have come from the north poles at the bottom of the magnets. These flux lines are flowing in the same direction and are mutually repulsive. This repulsion forces each magnet's flux lines in a direction away from the adjacent magnet, thereby distorting the inner magnetic field so that the lines of force are not centered within the tube, thereby making it unsuitable for operation of the magnetron beam switching tube. The closer magnets 21 and 21' are brought to each other, the more pronounced this distortion becomes. With usual field strengths and at a center-to-center separation of about 3 to 4 inches, this distortion causes the enclosed tubes to become inoperative. A center-to-center spacing greater than about 4 inches produces an unduly bulky assembly when several tubes are to be used, imposing a serious operating limitation upon multiple-tube applications.

Extensive experiments were performed to determine equipment and apparatus which could be used to permit operation of magnetron beam switching tubes in close proximity. When a bar 30 of iron was interposed between magnets as shown in Fig. 2, it was found that the external fields of magnets 21 and 21' were substantially confined to the low reluctance path through bar 30 and did not interact upon each other's internal field to any significant extent. As seen in Fig. 4, bar 30 achieves a shielding effect, in that flux lines are by-passed through it and do not extend as they do when bar 30 is absent. With bar 30 interposed, the internal magnetic field within magnets 21 and 21' are substantially the same as in an isolated magnet, as in Fig. 2; and the enclosed tubes function normally even though they are as close together as dimensions of magnets and bar will permit.

Clusters of more than two tubes also can be provided, as shown in Fig. 5. Bars 30 to 36 of low reluctance material such as iron or steel are interposed between magnets 21, 21', etc., along the lines between tube centers. In addition to the configuration shown, other cluster configurations can be used to take advantage of available space or to meet particular design requirements. Tube centers could be aligned along lines parallel to rectangular coordinates, along a ring, or following a helix or in other geometric patterns, and still utilize this means for keeping a close spacing between tubes.

The dimensions of bar 30 are not critical. A bar of cold rolled steel $\frac{1}{16}$ " x $\frac{1}{2}$ " x $1\frac{3}{4}$ " was found to give satisfactory results, and could vary from this size by a considerable percentage with no change in results. Other low reluctance, high permeability materials also can be used for bar 30.

There is thus provided a low reluctance by-pass or shield between magnetron beam switching tubes, preventing interaction of magnetic fields and permitting reliable operation of a plurality of such tubes, in close proximity.

What is claimed is:

1. A magnet structure for a plurality of magnetron tubes comprising a plurality of cylindrical magnets positioned in proximity on a common surface with their magnetic axes mutually parallel, and a plurality of bars of low reluctance material interposed one between each

pair of adjacent magnet walls of said cylindrical magnets with the major axes of said bars parallel to said magnetic axes.

5 2. A magnet structure for a plurality of magnetron tubes comprising a plurality of tubular magnets of substantially the same length positioned in close proximity with their magnetic axes mutually parallel and their magnetic poles in a common alignment, and a plurality of bars having one major axis of low magnetic reluctance material substantially coextensive with said cylindrical magnets and interposed between and in contact with adjacent walls of said cylindrical magnets with the major axes of said bars parallel to said magnetic axes.

10 3. A geometrically arranged cluster of magnetron beam switching tubes including a cylindrical magnet surrounding each tube and positioned in proximity to each other and in a common alignment, and a plurality of elongated ferro-magnetic bars interposed between adjacent tubes and substantially parallel with the magnetic axis of said cluster of tubes.

15 4. A compact cluster of magnetron beam switching tubes including similar cylindrical magnets surrounding each tube and positioned in a common magnetic field orientation and polarity, and a plurality of ferromagnetic bars of substantially the same length and the same thickness as said cylindrical magnet walls interposed between and in contact with adjacent walls thereof.

20 5. A cluster of vacuum tubes, each tube having an elongated central cathode and concentric arrays of electrodes in an evacuated envelope and a cylindrical magnet coaxially aligned with said cathode to produce a magnetic field parallel to and symmetrical about said cathode, with each tube of said cluster positioned in such proximity to another tube as to be within the external portions of the magnetic fields of that other tube whereby said external portions destroy the symmetry of the magnetic field about each tube's cathode, and a low reluctance member positioned between adjacent magnets to bypass said external portions of their magnetic field to thereby maintain the symmetry of each magnetic field about its respective cathode.

25 6. A magnet structure for a plurality of magnetron tubes comprising a plurality of hollow cylindrical magnets oriented in a common polarity and positioned on a common surface and in a compact cluster, wherein their magnetic fields are mutually disturbing so as to destroy the magnetic field distribution needed for operation of said magnetron tubes, and a plurality of low reluctance members having a length substantially the same as said cylindrical magnets and a thickness about the same as the walls of said magnets and a width less than their length, interposed between and in contact with said cylindrical magnets at their points of nearest approach to bypass the portions of said magnetic fields which are mutually disturbing.

30 7. A cluster of vacuum tubes, each tube having an elongated central cathode and concentric arrays of electrodes in an evacuated envelope and a cylindrical magnet coaxially aligned with said cathode to produce a magnetic field parallel to and symmetrical about said cathode, with each tube of said cluster positioned in such proximity to other tubes as to be within the external portions of the magnetic fields of said other tubes whereby said external portions destroy the symmetry of the magnetic field about each tube's cathode, and a plurality of low reluctance members positioned between adjacent magnets to bypass said external portions of their magnetic field and thereby restore the symmetry of each magnetic field about its respective cathode.
